tion of Pennsylvania

Application December 27, 1948, Serial No. 67,264

8 Claims. (Cl. 200—163)

1

My invention relates to an electric circuit controller, and particularly to a controller for shunting a track circuit and for controlling other circuits in a railway signal or control system.

It is sometimes necessary or convenient to provide a manually operable track switch in a section of a railway in which the signals are automatically controlled. In order to protect trains approaching such a switch, it is desirable to prevent manual operation of the switch until the signals have been set to stop for an adequate warning period. This may be done by providing a switch lock controlled by a manually movable member and a timer. The manual member may be operated at any time to set the signals governing the track approaching the switch to display a stop aspect, and start the timing mechanism running. After a predetermined time has expired, the timing mechanism releases the lock to permit manual actuation of the track switch.

The copending application for Letters Patent of the United States, Serial No. 749,833, of Howard A. Thompson, filed May 22, 1947, now Patent 2,539,937 issued January 30, 1951, for Traffic Protection Apparatus, illustrates a switch locking system of this type. Thompson shows a track switch operable by means of an electrically locked hand-throw lever, and a circuit controller operated by an auxiliary lever movable between normal and reverse positions. When this auxiliary lever is first moved away from its normal position, the circuit controller shunts the track circuit, thereby setting the signals governing trains approaching the switch to stop. As the motion of the manual auxiliary lever to its reverse position is completed, it actuates additional contacts to initiate the operation of a timing mechanism which eventually releases the electric lock on the hand-throw lever of the track switch.

The present invention relates to a circuit controller for use in a system of the type described in the Thompson application.

An electric circuit controller for shunting a railway track circuit and for controlling additional circuits, if mounted on the railway ties, is subject to severe conditions of vibration. This vibration will cause undue wear between the parts if relative motion of the parts is not prevented.

Where such a controller is used to shunt a track circuit on an electric railway, it must have high current carrying capacity. On electrified railways, the rails are commonly used as a current flow path, and unbalanced resistance conditions in the opposite rails may cause high current flow through track shunting contacts. Such a controller must therefore have heavy duty contacts. If the controller is required to additional-

2

ly control other circuits, for example signal or control circuits, then additional light duty contacts must be provided in the controller.

Where a controller is to be mounted on the ties of a railway, it is desirable that its overall height be low enough so that it may be mounted between the rails of a track without projecting sufficiently above the track to foul any portion of the equipment passing over it.

10 An object of my invention is therefore to provide an improved electric circuit controller of high current carrying capacity.

Another object is to provide an electrical circuit controller which may be subjected to severe vibration without producing undue wear between the moving parts of the controller.

15 A further object is to provide an improved controller including a set of heavy duty contacts and a set of light duty contacts in the same casing and operated by movement of the same control member.

20 A further object is to provide an improved controller of the type described in a compact structure so arranged that it may be mounted between the rails of a railway track without projecting far enough above the track rails to foul rolling stock passing over it.

25 According to my invention, I achieve these objects by using elongated fixed and movable contacts mounted horizontally, and support the movable contact so that it is moved horizontally to open and close the circuit. This construction aids in keeping the overall height of my controller at a minimum. In order to provide high current carrying capacity, one of the contacts is made in the form of a flat bar having convex upper and lower surfaces. This bar moves between a pair of flat spring contacts which, in their disengaged condition, are spaced apart by a distance somewhat less than the distance between the opposite convex surfaces on the bar contacts. In this way, a line contact is maintained between the bar and the flat springs.

30 35 40 45 The controller is operated by an external manual lever which rotates a shaft through an angle of 180°. This shaft is connected to the movable contact supporting structure through a crank and pitman to provide a linear movement of the movable contact upon rotation of the shaft.

45 50 55 The movable contact is loosely mounted on its support so that minor misalignments between the fixed and movable contacts may be accommodated. The spring contact structure is effective when the contacts are closed to take up all lost motion in the contact support operating mechanism, so as to prevent wear in the operating parts due to vibration. A stationarily sup-

ported spring is provided in the path of movement of the movable contacts so as to engage those contacts as soon as they separate from the stationary contact. This spring device places the movable contact and the contact operating element under tension, and thereby is effective when the contacts are open to take up all lost motion in either the loose mounting of the movable contact or in the bearings of the shaft, crank, and pitman.

The light duty contact assembly is mounted on a bridge structure above the pitman and is operated by a cam adjustably fixed on the crank shaft.

Other objects and advantages of my invention will become apparent as the description proceeds.

I shall describe two forms of circuit controllers embodying my invention, and shall then point out the novel features thereof in claims.

In the drawings, Fig. 1 is a cross-sectional view of one form of electric circuit controller constructed in accordance with my invention, taken along the line I—I of Figs. 2 and 3, looking in the direction of the arrows. Fig. 2 is a plan view of the controller of Fig. 1, with the cover removed. Fig. 3 is an elevational view of the left-hand end of the controller of Figs. 1 and 2. Fig. 4 is a plan view of a railway track layout showing certain railway traffic control apparatus, including a circuit controller built according to Figs. 1-3, mounted between the rails. Fig. 5 is an elevational view of the control apparatus of Fig. 4. Fig. 6 is a cross-sectional view of a modified form of controller built in accordance with my invention. Fig. 7 is a plan view of the controller of Fig. 6 with the cover removed. Fig. 8 is a detail cross-sectional view taken along the line VIII—VIII of Fig. 7. Fig. 9 is a plan view similar to Fig. 4 illustrating the mounting of railway traffic control apparatus including a circuit controller built according to Figs. 6 and 7. Fig. 10 is an elevational view of the control apparatus of Fig. 9.

Figs. 1 to 3

Referring to the drawings, there is shown in Figs. 1 to 3 a controller generally indicated at 1. The controller 1 includes a casing 2 having mounting feet 3 and a removable cover 4. A latch 5, of known construction, is provided to hold the cover in place. A squared shaft 6 projects outside the casing and carries an operating lever 7 having a handle 8.

One end of the casing 4 is open, and is closed by means of an insulating plate 9 attached to the casing by means of bolts 10. Four contact supporting blocks 11, 12, 13, and 14 (see Fig. 3) are attached to the insulating plate 9 by means of bolts 15. The blocks 11, 12, 13, and 14 carry electrical terminals 16, 17, 18, and 19, respectively, which extend outwardly through the insulating plate 9. The outside ends of these terminals are adapted for the attachment of suitable heavy current conductors for shunting the rails of a track circuit. Inside the casing 4, each of the contact supporting blocks carries a pair of spaced spring contact blades 20. These blades 20 are elongated in the horizontal plane and are slotted, as at 20a, to permit independent movement of the portions between the slots, so as to accommodate misalignment of the contacts.

It should be noted that the blades 20 on the upper contact supporting blocks 11 and 12 are horizontally aligned with each other and that the blades 20 on the lower contact supporting

blocks 13 and 14 are likewise horizontally aligned with each other. The upper set of blades 20 is adapted to be bridged by a movable contact bar 21, and the lower set of blades 23 may be bridged by a movable contact bar 22.

The bars 21 and 22 are formed with relatively narrow edge portions 21a, 21b, 22a, and 22b and wider central portions 21c and 22c having convex surfaces. The convex surfaces 21c and 22c are made wider than the distance between the spring blades 20, so that when the contact bars 21 and 22 move between the blades 20, those blades ride on the convex surfaces, thereby producing substantially a line contact between the blades and the contact bars.

The advantage of a line contact is that it provides high current carrying capacity while the force necessary to operate the movable contacts is held at a minimum. This advantage is gained by arranging the parts to produce high contact pressures so that correspondingly high current densities may be used.

A line contact could alternatively be obtained through the use of a flat bar contact and a contoured spring contact. The construction shown is greatly to be preferred, however, since it is much easier to maintain accurate dimensions in a solid bar with a convex contour than it is in a relatively thin flexible spring with a corresponding contour. The dimensions of the bar and spring contacts are very important in this construction, because these dimensions are major factors in determining the contact pressure and hence the allowable current density.

hence the allowable current density.

5 The opposite ends of the contact bars 21 and 22 are loosely received in recesses 23 formed in a pair of movable contact supporting slide blocks 24, of insulating material. Each of the slide blocks 24 moves between a lower guiding surface 25 formed in the casing 2 and an upper guiding surface 26 formed on the lower side of a rail 27 attached to the side of casing 2 by means of bolts 28.

15   The slide blocks 24 are connected by means of a crosshead rod 29, which is in turn connected by two pitmans 30 to crank arms 31 attached to the shaft 6. Each pitman 30 is connected to its associated crank arm 31 by means of a pin 32. Each pitman 30 is curved, as indicated at 30a in Fig. 1 to permit rotation of the shaft 6 further in a counterclockwise direction (as viewed in Fig. 1) than would otherwise be possible. The crank arms 31 are rigidly attached to the shaft 6 by any suitable means, as for example 55 by using a split crank arm as indicated at 31a, and a bolt 31b to tighten the opposite parts of the crank arm together.

At all bearings, such as the bearings of shaft 6, the pins 32, and the crosshead rod 29, a certain small clearance must be allowed so that the relatively rotatable members can turn freely and without binding. A controller intended to be mounted on a railway track is likely to be subjected to very severe conditions of vibration. The vibration tends to cause the relatively rotatable parts to move relative to each other, because of the clearances between them, thereby causing friction and wear of the parts. Also, the vibration might cause movement and wear of the contact bars 21 and 22 in their sockets 23 unless some means is provided to prevent it.

I prevent wear due to such vibration conditions by the provision of two springs 33 mounted on a bracket 34 so that they are aligned with the contact bars 21 and 22. The bracket 34 is

attached as by bolts 35 to the bottom of the casing 4. The springs 33 are so arranged that as the contact bars 21 and 22 move to their normal open circuit position, as shown in the drawings, they engage the springs 33. The springs 33 thereby hold the contact bars 21 and 22 tightly against the left-hand ends of their supporting recesses 23, as viewed in Fig. 1. At the same time, the springs 33 place all the bearings associated with the pitman 30, crank 31, and shaft 6 under tension, so that all lost motion due to clearances between these parts is taken up. Since the parts are held firmly against each other, they cannot rub or pound so as to cause excessive wear.

The stationary contact assembly, including the mounting plate 9, the contact supporting blocks 11, 12, 13, and 14, the connectors 16, 17, 18, and 19, and the contact blades 20 is removable as a unit from the casing by taking out the attaching bolts 10.

The light duty contacts of my controller are mounted on a pair of supports 36 which are removably attached to the bottom of the casing adjacent the opposite sides thereof. An insulating plate 37 is attached to the tops of the supports 36, and bridges the pitmans 30. The plate 37 carries a row of fixed contacts 38, and a row of movable contacts 39, all of the leaf spring type. The movable contacts 39 are longer than the fixed contacts 38, and their ends project into suitable notches 40 formed in an insulating member 41. The member 41 is carried by a yoke 42, whose ends are pivotally attached to a shaft 43 journaled in the supports 36.

The insulating member 41 is carried on a cross bar 42a of yoke 42. At the ends of the cross bar 42a the yoke is provided with bolts 44 which engage hubs 45 formed in the casing 2, in which hubs the shaft 6 turns. A pair of biasing springs 46 have their upper ends connected to the yoke 42 and their lower ends connected to brackets 47, which are attached to the casing 2 by certain of the bolts which hold the supports 36. The biasing springs 46 hold the yoke 42 down so that screws 44 engage the hubs 45. The insulating support 41 is then in the path of movement of an adjustable cam 48 mounted on the shaft 6. With this construction, the entire light duty contact assembly including supports 36, plate 37, contacts 38-39, yoke 42, and springs 46 may be removed as a unit for inspection or repair without disturbing the heavy duty contacts or their operating mechanism.

Cam 48 comprises an operating portion 48a and a clamping portion 48b secured together by means of an adjusting screw 48c and a clamping bolt 48d. The adjusting screw 48c cooperates intermediate its ends with an annular threaded groove 49 formed in the shaft 6 in such manner that by first backing off the clamping bolt 48d and then rotating the adjusting screw 48c the cam can be readily rotated to any desired angular position relative to the shaft. After the desired adjustment has been made, the clamping bolt is again tightened and the cam will then be securely held in its adjusted position.

The lower end of insulator 41 lies in the path of the operating surface of cam 48. When cam 48 engages the insulator 41, it moves upwardly, carrying with it the movable contacts 39 into engagement with their associated stationary contacts 38.

By means of adjustable cam 48, any desired

relationship may be established between the angular position of shaft 6 at which the heavy duty contacts are operated and the angular position of shaft 6 at which the light duty contacts are operated. For example, where the heavy duty contacts are used to shunt a track circuit, then it is desired to have the light duty contacts set so that their circuit is not completed until the motion of the hand operating lever 7 to its reverse position is substantially complete. This mode of operation will be secured with the cam adjusted as shown in the drawings. With the cam in this position, the light duty contacts are not operated until the shoulder 48e of the cam moves around and engages the insulator 41.

The insulating block 37 is provided with suitable terminals 50 connected to each of the contacts 38 and 39. The casing is provided with conduit outlets 51 for permitting the passage of wires leading to the terminals.

It may be seen that upon clockwise rotation of the shaft 6 by the manual lever 7, the contact bars 21 and 22 will be moved to the left to engage their respective stationary contact blades 20. After this engagement has been made, the cam 48 will thereafter operate the light duty contacts 38 and 39 to their closed positions.

Both the fixed and movable heavy duty contacts are elongated horizontally to obtain the required size and current carrying capacity. This construction of the contacts and the mounting of the movable contacts for horizontal movement allow my circuit controller to be constructed with a low overall height so that it may be readily mounted between the rails of a railway track.

Figs 4 and 5

There is shown in these figures railway traffic controlling apparatus including an electric circuit controller 1 of the type described in detail in connection with Figs. 1 to 3. This apparatus illustrates one manner in which that circuit controller may be utilized in practice. There is shown a portion of a crossover track between two main tracks, including rails 52 and 53 supported on ties 54. The switches at the opposite ends of the crossover track (not shown) may be provided with any suitable manually operable switch stands for moving the switches between their normal and reverse positions. These switches are locked in their normal position by means of locking mechanisms of the type illustrated in Letters Patent of the United States No. 1,654,023, issued December 27, 1927, to C. C. 40 Thor. The locking mechanisms for both switches are controlled simultaneously by a pipe line 55 extending between the switch stands. When the pipe line 55 is in the position shown in the drawings, both switches are locked, and it is shiftable endwise from that position to unlock both switches simultaneously. The pipe line 55 may be shifted by means of an adjustable link 56 connected between a point on the pipe line and a crank pin 57 carried by a crank arm 58 on a crankshaft 59 supported by a center throw lever stand 60. The crankshaft 59 also carries a hand-throw lever 61 by which the shaft 59 and crank 58 may be rotated. The hand-throw lever 61 is locked in the position shown in the drawings by means of an electric lock generally indicated at 62, which is preferably of the type shown and claimed in the copending application for Letters Patent of the United States, Serial No. 67,392, of Herbert L. Bone, entitled Railway Traffic Controlling Apparatus, filed De-

ember 27, 1948, now Patent No. 2,631,228 issued March 10, 1953.

For the purposes of the present application, it is believed sufficient to state that the lock 62 includes a latch 63 operated by a pedal 64. The latch 63 and pedal 64 are held in the position shown in the drawings by an internal electric locking mechanism, in which position the latch 63 extends over the hand-throw lever 61 and holds it down.

The lock 62 and the center throw lever stand 60 are mounted on a plate 65 attached to the ties 54.

When the electric lock 62 is deenergized, the pedal 64 is locked so that latch 63 cannot be released. When the electric lock 62 is energized, the pedal 64 may be depressed to release latch 63.

In the construction shown in the drawings, downward movement of the foot pedal 64 is further prevented by a bolt 66 which moves in a slot 67 attached to the plate 65. In the position shown, the bolt 66 lies immediately under the pedal 64 and prevents its downward movement. The opposite end of bolt 66 is connected through an adjustable link 68 to a pin 69 which passes through an eccentric hub 70 formed in the hand-throw lever 7 of the circuit controller 1.

The hand-throw lever 61 is provided with the usual lever lock rod 71, which cooperates with the pedal 64 to prevent restoration of the latch 63 to its latching position while the hand-throw lever 61 is away from its normal position.

As previously mentioned, the heavy duty contacts in the electric circuit controller 1 are effective when the hand-throw lever 7 is reversed from the position shown to shunt the track circuits, and thereby set the signals associated with the main line tracks at stop. At the same time, the light duty contacts of the circuit controller 1 are effective to initiate operation of a timing mechanism which causes the electric lock 62 to be energized after a predetermined period of time. Operation of the hand-throw lever 7 from the normal position shown in the drawing to the reverse position 180° away from the normal position is also effective to move the bolt 66 out from under the pedal 64 of the electric lock 62, so that as soon as the predetermined time has expired, the pedal may be depressed to release the hand-throw lever 61. As soon as the hand-throw lever 61 is operated, the locks on both the switches are released and the switches may be thrown so that the crossover track may be used.

When it is desired to restore the crossover track to its normal operating condition, both switches are first restored to their normal positions, and the hand-throw lever 61 of the locking mechanism is then restored to normal. The pedal 64 and latch 63 are restored to their latching positions, and then the hand-throw lever 7 of the circuit controller 1 may be restored to its normal position. It should be noted that the bolt 66 interlocks the circuit controller 1 with the electric lock 62 so that the circuit controller lever 7 cannot be restored to its normal position until the pedal 64 is returned to its normal lever latching position.

Figs. 6 to 8

There is shown in these figures another form of electric circuit controller, generally indicated by the reference character 72, which is adapted for use in an installation to be described herein-after and which includes a modified form of heavy duty contact mechanism.

The circuit controller 72 includes a casing 13

having a cover 14. Near the left end of casing 13, as it appears in the drawings, a shaft 75 extends transversely through the casing and outwardly beyond both sides of the casing. On one end of the shaft 75 is fixed a hand-throw lever 76 and on the opposite end of the shaft 75 is fixed a crank arm 77.

A circuit controller operating shaft 78 also extends through the casing transversely and has one end projecting outside the casing and carrying a hand operating lever 79.

Inside the casing 13, the shaft 78 is arranged to operate a set of heavy duty contacts and a set of light duty contacts. The mechanism for operating the heavy duty contacts includes a pair of crank arms 80 fixed on the shaft 78 by suitable means and connected by crank pins 81 to a pair of pitmans 82.

The pitmans 82 are provided with lateral curves 82a to permit rotation of the crankshaft 79 farther in a counterclockwise direction without fouling the shaft than would otherwise be the case. The opposite ends of the pitmans 82 are pivotally connected to a crosshead rod 83 journaled at its ends in a pair of slide blocks 84. Each of the slide blocks 84 moves between a lower guiding surface 85 cast integrally with the casing 13 and an upper guide rail 86 bolted to the side of the casing 13.

The slide blocks 84 support the opposite ends of an insulating plate 87, which carries the movable contacts of the heavy duty circuit controller. These slide blocks 84 are provided with apertures 84a which loosely receive projections 87a on the ends of the insulating plate 87, so that the latter is loosely mounted at its ends in the slide blocks 84.

Mounted on the insulating plate 87 are two sets of heavy duty contacts, the sets being generally indicated respectively by the reference characters 88 and 89. Each set comprises two channel-shaped spring members 90 and 91 (see Fig. 6) of different widths. These channel-shaped members are held together in nested relation on the insulating plate 87 by means of bolts 92. The spring members 90 and 91 are slotted, as shown at 90a in Fig. 7, so as to accommodate misalignment of the contacts.

Each set of movable heavy duty contacts 88 and 89 cooperates with a pair of upper and lower stationary contact bars 93 and 94. The contact bars 93 and 94 are mounted by means of bolts 95 on an insulating terminal board 96 which closes an open end of the casing 13. The contact bars 93 and 94 are provided with integral extensions 93a and 94a which pass through the insulating board 96 and are provided outside the casing 13 with terminal lugs 97.

The contact bars 93 and 94 are provided with relatively thin edge portions 93a and 94a narrower than the space between the spring contact members 90 and 91, and relatively thick central portions having convex surfaces 93b and 94b. These convex surfaces are made wider than the distance between the spring blades 90 and 91, so that when the blades engage the contact bars, a line contact is produced.

A spring loading mechanism is provided for the heavy duty movable contact structure to prevent rattling and wear due to vibration. This mechanism includes a U-shaped bracket 98 mounted on the bottom of the casing 13. Two spring rods 99 extend through apertures in the opposite sides of the bracket 98. Each spring rod 99 carries a spring retaining washer 100.

A spring 101 encircles each spring rod between the left side of the U-shaped bracket 98 and the spring retaining washer 100. The springs 101 bias the spring rods 99 to a position in which the washers 100 engage the inner surface of the right-hand side of the U-shaped bracket 98. When the movable heavy duty contact structure is in its normal position, as shown, the insulating plate 87 is moved against the ends of the spring rods 99 so as to compress the springs 101. The springs 101 are thereby effective to take up all lost motion between the plate 87 and the slide blocks 84, and are also effective to take up the lost motion in the bearings of the mechanism which drives the slide blocks 84.

The light duty contact structure of my controller is mounted on a pair of supports 102 which are attached to the bottom of the casing 73 adjacent the opposite sides thereof by means of bolts 103. An insulating plate 104 is mounted on the supports 102, spanning the pitmans 82. The plate 104 carries a row of fixed contacts 105 and a row of movable contacts 106, all of the leaf spring type. The movable contacts 106 are longer than the fixed contacts 105, and their ends project into suitable notches formed in an insulating member 107. The member 107 is carried by a yoke 108, whose ends are pivotally mounted on pins 109 set in the supports 102. The yoke 108 has a crossbar 108a which carries the insulating member 41. The lower edge of crossbar 108a is contoured to provide a cam follower which cooperates with a cam 110 attached to the shaft 78. A spring 108b, connected between yoke 108 and a bracket 108c held in place by one of the bolts 103, biases the follower into engagement with cam 110. As in the case of the controller of Figs. 1-3, the entire light duty contact assembly may be removed for inspection or repair without disturbing the heavy duty contacts.

Cam 110 (see Fig. 8) comprises two portions 110a and 110b secured together on the shaft 78 by means of a clamping bolt 111. An adjusting screw 112 passes freely through openings in the cam portions 110a and 110b and is held against longitudinal movement with respect to those cam portions by its head and by a lock nut 113, respectively. The adjusting screw 112 cooperates intermediate its ends with an annular threaded groove 78a formed in the shaft 78. By loosening the clamping bolt 111 and rotating the adjusting screw 112, the cam may be readily moved to any desired angular position relative to the shaft. If the clamping bolt is again tightened, the cam will then be securely held in its adjusted position.

By adjustment of cam 110, any desired relationship may be established between the angular position of shaft 78 at which the heavy duty contacts close and the angular position at which the light duty contacts close.

When the circuit controller shaft 78 is operated by the lever 79 through 180° clockwise from the position shown in the drawings, then, with the cam adjustment illustrated, the heavy duty contacts will close first, and the light duty contacts will close later when the shoulder 110c of cam 110 engages the cam follower 108a.

Figs. 9 and 10

These figures illustrate the installation of a circuit controller 72 such as that shown in Figs. 6 to 8, for use in connection with a center throw lever for releasing the locks on switches at the

opposite ends of a crossover track between two main tracks. The apparatus of Figs. 9 and 10 is intended for the same general purpose as the apparatus shown and described in connection with Figs. 4 and 5.

In the arrangement of Figs. 9 and 10, the hand-throw lever 76 serves as the center throw lever for operating the lock releasing pipe line. To this end, a pin 114 on the crank arm 77 is connected through a link 115 to the pipe line to be shifted. The circuit controller 72 is attached to a mounting plate 116 bolted to the ties of the railway track. An electric lock 117 for the hand-throw lever 76 is also mounted on the plate 116. The electric lock 117 is provided with a latch 118 which holds the center throw lever 76 down, and a pedal 119 by means of which the latch 118 may be released whenever the electric lock 117 is energized.

Any suitable electric lock mechanism may be used, but I prefer to use one of the type disclosed in the copending application for Letters Patent of the United States of Herbert L. Bone, Serial No. 67,392, filed December 27, 1948, now Patent No. 2,631,228, issued March 10, 1953, entitled Railway Traffic Controlling Apparatus.

A pedal lock rod 120, of conventional construction, is attached to the hand-throw lever 76, and cooperates with the pedal 119 to prevent return of the pedal to its normal latching position when the hand-throw lever 76 has been moved out of the jaw of the latch. A bolt 121 is provided, which, in the position shown, has one end projecting under the pedal 119 so as to prevent its downward movement in a latch releasing direction. The bolt 121 moves in a guide 122 attached to the mounting plate 116, and its opposite end is pivotally connected to a link 123 whose opposite end is in turn pivotally connected to an eccentric pin on the hand-throw lever 79.

When the parts are in the positions shown in the drawings, and it is desired to use the crossover track, then the switchman must first operate the circuit controller by moving the hand-throw lever 79 from the position shown through 180° to its reverse position. During this movement, the heavy duty contacts in the circuit controller shunt the track circuits so that the signals on the associated main line track are set at stop. At the same time, the end of bolt 121 moves out from under pedal 119. The light duty contacts of the circuit controller 72 initiate the operation of a timing mechanism which, at the end of a predetermined period of time, energizes the electric lock 117, so that thereafter depression of the pedal 119 releases the latch 118 and allows operation of the center throw lever 76 to release the locks on the track switches. After the train has passed over the crossover, it may be restored to its previous condition by throwing the two switches to their normal positions, restoring their locks by returning the hand-throw lever 76 to its normal position, locking that lever by returning the pedal 119 to its normal position, and then operating the hand lever 79 of the circuit controller 72 to its normal position.

It should be noted that the bolt 121 prevents restoration of the circuit controller lever 79 to its normal position before the pedal 119 has been restored to its normal position.

A pair of brackets 124 are attached to the plate 116 so as to receive the lever 79 in its normal and reverse positions. The brackets 124 are provided with suitable openings for the application of padlocks or other devices to prevent oper-

11

ation by unauthorized persons, and to hold the lever down during passage of a train over the controller.

Although I have herein shown and described only two forms of circuit controllers embodying my invention, it is understood that various changes and modifications may be made therein within the scope of the appended claims without departing from the spirit and scope of my invention.

Having thus described my invention, what I claim is:

1. An electric circuit controller comprising fixed and movable contact structures, a support for the movable contact structure including a member at each end of said structure, each said member having a recess slightly larger than the adjacent end of the contact structure to receive said adjacent end loosely therein, and means connecting said support members for concurrent movement, said recesses permitting limited lateral movement of said movable structure to compensate for misalignment of the contact structures.

2. An electric circuit controller comprising a stationary contact, a contact movable along a linear path to engage and disengage said stationary contact, a rotatable shaft, a crank on said shaft, a pitman connecting said crank and said movable contact, and a spring located in the path of movement of the movable contact so as to be engaged thereby upon disengagement of said contacts, said spring being effective to take up all lost motion in the connection of said crank, shaft and pitman.

3. An electric circuit controller comprising fixed and movable contact structures, a support for said movable contact structure, means loosely connecting said movable structure to its support to permit limited lateral movement of said one structure to compensate for misalignment between said contact structures, and a spring located in the path of movement of said movable contact structure so as to be engaged thereby upon disengagement of said contacts, said spring being effective to prevent rattling of said movable contact structure in its loose support when the contact structures are disengaged.

4. An electric circuit controller as in claim 3, in which said support is slidably movable along a linear path, and including a shaft, means for rotating said shaft, a crank on said shaft, and a pitman connecting said crank and said support so that rotation of said shaft causes engagement and disengagement of said contact structures, said spring being also effective to take up all lost motion in the connections of said shaft, crank and pitman.

5. An electric circuit controller comprising a contact support, a pair of spaced contacts fixed to said support, a contact member, a contact support for said contact member including two spaced, slidably mounted members having recesses for receiving the adjacent ends of said contact member with clearance to permit limited movement of said contact member to compensate for misalignment of the spaced contacts and the contact member, and means connecting said slidably mounted members for concurrent movement to engage and disengage said contacts and contact member.

6. An electric circuit controller comprising a contact support, a pair of spaced contacts fixed to said support, a contact member, a contact sup-

12

port for said contact member including two spaced, slidably mounted members having recesses for receiving the adjacent ends of said contact member with clearance to permit limited movement of said contact member to compensate for misalignment of the spaced contacts and the contact member, means connecting said slidably mounted members for concurrent movement to engage and disengage said contacts and contact member, and a spring located in the path of movement of said contact member so as to be engaged thereby upon disengagement of the spaced contacts and the contact member to prevent rattling of said contact member in the recesses of its supporting slidably mounted members.

7. An electric circuit controller comprising two contact supports, a contact member on one support, and a pair of spaced contacts on the other support, spaced slidably mounted members having recesses therein, projections on one of said supports receivable within said recesses with clearance to permit limited movement of said contact support to compensate for misalignment of the spaced contacts and the contact member, and means connecting said slidably mounted members for concurrent movement to engage and disengage said spaced contacts and contact member.

8. An electric circuit controller comprising two contact supports, a contact member on one support, and a pair of spaced contacts on the other support, spaced slidably mounted members having recesses therein, projections on one of said supports receivable within said recesses with clearance to permit limited movement of said contact support to compensate for misalignment of the spaced contacts and the contact member, means connecting said slidably mounted members for concurrent movement to engage and disengage said spaced contacts and contact member, and a spring located in the path of movement of the contact support carried by the slidably mounted members so as to be engaged thereby upon disengagement of the spaced contacts and the contact member to prevent rattling of said contact support in the recesses of its supporting slidably mounted members.

WILLIAM R. GRACEY, JR.
